UNITED STATES PATENT OFFICE.

WILLIAM H. HUFF, OF HAMLET, NORTH CAROLINA.

ADJUSTABLE TIE PLATE.

Application filed December 21, 1926. Serial No. 156,172.

The present invention is directed to improvements in adjustable tie plates for rails.

The primary object of the invention is to provide a device of this character constructed and arranged in such manner that when the rails shift and lose their standard gage the plate can be adjusted to maintain the rails in proper gage.

Another object of the invention is to provide a device of this character including a rail clamping plate capable of being adjusted upon the tie plate in order to maintain the rails in proper gage whether the shifting thereof has been slight or abnormal.

Another object of the invention is to provide means whereby the clamping plate will be rigidly maintained in any of its adjusted positions.

In the accompanying drawings:

Figure 1 is a top plan view of the device showing the normal position of the clamping plate, the rail being indicated in dotted lines.

Figure 2 is a sectional view on line 2—2 of Figure 1.

Figure 3 is a sectional view on line 3—3 of Figure 1.

Figure 4 is a sectional view on line 4—4 of Figure 1.

Figure 5 is a perspective view of the clamping plate.

Figure 6 is a perspective view of the tie plate.

Figure 7 is a fragmentary end view of a modified form of the invention.

Referring to the drawings, 1 designates a tie plate, rectangular in shape, and has formed upon its longitudinal edges V-shaped grooves 2, the rear ends of said grooves 2, the rear ends of said grooves 40 stopping short of the outer end of the plate to provide shoulders 3, the purpose of which will be explained later. The plate 1 is provided with rectangular openings 4 and 5 and an adjacent longitudinal slot 6, there being 45 a similar slot 7 formed in the said plate and disposed diagonally with respect to the slot 6. It will be observed that the upper edges of the outer walls of the grooves 2 are below the plane of the plate 1, the purpose of 50 which will appear later.

Associated with the plate 1 is a clamping plate 8, said plate having arms 9 projected in parallel relation therefrom, said arms being V-shaped in cross section to correspond 55 to the shape of the grooves 2, the upper surfaces thereof being below the plane of the

plate 8 and so formed that the outer ends constitute stops 10 which abut the shoulders 3 when the plate 8 is in its normal, or initial position upon the plate 1. In this manner 60 the plate 8 is held against endwise movement in one direction. The plate 8 is provided with rectangular spike receiving openings 11 and 12, arranged in groups, one group comprising two openings, while the 65 other group comprises three openings, there being a notch 13 formed in the inner edge of the plate 8, as clearly shown in Figure 5 of the drawings.

The inner ends of the arms 9 are formed 70 with cleats 14 designed to engage the inner edge of the base 15 of the rail 16, as indicated in dotted lines in Figure 2 of the drawings.

The under surface of the plate 1 is provided with transverse ribs 17 adapted to bite into the tie to prevent creeping thereof.

In order that the plate 1 may be anchored to the tie an opening 18 is formed 80 adjacent the inner end thereof for the reception of a spike. In this manner the plate 1 may be maintained in its proper position upon the tie to prevent dislodgment thereof when the rails are bent set.

Normally the plate 8 is in the position 85 shown in full lines in Figure 1 and at which time the notch 13 thereof coincides with the outer end of the slot 6 for the reception of a rail spike, there being also a spike engaged in the slot 7. Since the cleats 14 engage the 90 inner edge of the rail base the rail will be maintained firmly in place upon the tie plate.

The opening 4 of the plate 1 will be in registration with the innermost opening 12 95 of the plate 8, and if desired a spike may be then driven in these openings for engaging the tie.

When the rails shift and lose their gage 100 it is only necessary to remove the spikes and lift the rails from the plate 1, whereupon the plate 8 may be slid inwardly until the innermost opening 11 thereof fully registers with the opening 5 of the plate 1, whereupon the rail is replaced and spikes driven 105 in the registering openings, as well as in the notch 13 and slot 6 and in the slot 7, and at which time the plate 8 and its arms 9 assume the position as shown in dotted lines 110 in Figure 2 of the drawings. If further adjustment is required the plate 8 may be moved further inwardly until the central

opening 12 registers with the opening 4 and if still further adjustment is desired the plate 8 may be moved inwardly until the outermost opening 12 registers with the opening 4.

It will be obvious that upon adjustment of the plate 8, the stops 10 of the arms will disengage the shoulders 3 but owing to the presence of the spikes in the respective registering openings 11 and 5 and 12 and 4, outward movement of the plates is prevented. In other words, when thus engaged the spikes serve the same function as the shoulders 3 and stops 10 inasmuch as they prevent outward sliding movement of the plate 8. Owing to the fact that the outer walls of the grooves 2 are below the plane of the plate 1 they will be prevented from being marred when rails are dropped thereon when laying tracks, and in this manner any possibility of distorting the grooves and preventing free sliding of the arms therein is positively prevented.

When the rails are resting upon the plates 1 they will also engage upon the arms 9, thus maintaining the same firmly in the respective grooves 2.

In Figure 7 the clamping plate 8 is shown provided with a brace arm 19 designed to have its upper end engaged with the ball of the rails, this construction being particularly well adapted for use in connection with switch points.

Obviously it is necessary to plug the holes in the tie after the spikes have been withdrawn to give purchase for the succeeding spikes. This can be readily accomplished upon removing the clamping plate and driving wooden fillers in the vacated spike holes.

Having thus described the invention, I claim:

1. The combination with a tie plate, of a clamping plate slidably mounted thereon, and having arms slidably interlocked with the tie plate and provided with cleats at their inner ends which coact with the inner edge of the plate to confine the base of the rail.

2. The combination with a tie plate having grooves therein adjacent its marginal edges with the outer walls of the grooves below the plane of the plate, of a clamping plate having arms thereon for slidable engagement in the grooves, and having rail engaging cleats at their inner ends, and

means for locking the clamping plate in adjusted positions upon the tie plate.

3. The combination with a tie plate having grooves therein, shoulders at one of their ends, a clamping plate having arms carried thereby for slidably engaging the grooves, the outer ends of the arms constituting stops for engagement with the shoulders to limit the sliding movement of the arms, and cleats at the inner ends of the arms to coact with the inner edge of the plate to confine the base of the rail.

4. The combination with a tie plate having openings therein, of a clamping plate slidably adjustable upon the tie plate and having groups of openings therein for selected registration with the openings of the tie plate for the reception of securing devices.

5. The combination with a tie plate having openings and a slot therein, of a clamping plate having groups of openings therein for selected registration with the respective openings of the tie plate, said clamping plate having a notch in one edge for registration with said slot, and securing devices engageable in the registering openings and notch and slot for securing the clamping plate in adjusted positions upon the tie plate.

6. The combination with a tie plate having longitudinal grooves, of a clamping plate having arms slidably adjustable in the grooves, and cleats upon the ends of the arms for engaging one edge of the rail base when the clamping plate is engaged with the other edge thereof.

7. The combination with a tie plate having longitudinal grooves formed in the upper face thereof, a clamping plate having arms carried thereby for slidable engagement in the grooves, the outer walls of the grooves being below the plane of the upper surface of the tie plate.

8. The combination with a tie plate having spike receiving openings therein, of a clamping plate adjustably mounted on the tie plate and having openings therein arranged in groups, the openings of the groups being adapted to be successively brought into registration with the respective openings in the tie plate when the clamping plate is adjusted.

In testimony whereof I affix my signature.

WILLIAM H. HUFF. [L. S.]
